Term of patent 14 years

Int. Cl. D14—99

U.S. Cl. D26—14

FIG. 7.

FIG. 1 is a left side elevational view of a combined stylus unit and a stylus guard therefor, showing my new design, the right side view being substantially the mirror image thereof;

FIG. 2 is a front elevational view;

FIG. 3 is a top view;

FIG. 4 is a bottom view;

FIG. 5 is a rear elevational view, looking in the direction of arrows 5-5 of FIG. 1;

FIG. 6 is a cross-section taken through line 6-6 of FIG. 3, looking in the direction of arrows 6-6; and

FIG. 7 is a perspective of the structure illustrated in FIGS. 1 through 6.

I claim:

The ornamental design for a combined stylus unit and stylus guard therefor, as shown and described.
